TITUS G. LE CLAIR AND CHARLES M. GROSS, OF CHICAGO, ILLINOIS

ROTARY SWITCH AND SWITCHING SYSTEM

Application filed June 28, 1930. Serial No. 464,554.

This invention relates to electric power systems in general and more particularly to switching means for effecting the switching connections between a line circuit, a regulator, and a main and a transfer bus.

Consider a switching station of the type provided with a main bus, a transfer bus, and a plurality of outgoing line circuits. It is customary to provide a regulator for each circuit and to provide switching means for connecting each of the outgoing circuits to the main bus or to the transfer bus at will. Switching means is also provided for feeding the transfer bus from the main bus either regulated or unregulated as desired and for connecting the outgoing line circuit to the main bus either regulated or unregulated as desired. The switching means usually comprises disconnecting switches which are opened or closed by the operator by means of an insulated stick. The term "disconnect switches" is generally understood to mean switches for circuits of comparatively high voltage or current and never used to interrupt a circuit under load, but opened only when no current is flowing therethrough, as for completely isolating a particular piece of apparatus from the line so that it may, for example, be inspected or repaired, or for affecting switching operations between points at substantially the same voltage. It is well known that disconnect switches should not be operated under load since they are not designed for such operation and, should such a switch be operated under those conditions the operator is exposing himself to a great danger and, in addition, severe damage may be done to the switch. It is one of the objects of the present invention to so interrelate the disconnect switches for obtaining the desired circuit connections that it will be impossible to obtain a wrong sequence of operation and wherein, when the circuit is opened, the operator will not be in danger of being burned by the arc formed should the circuit be alive.

It is a further object of the present invention to provide a switching arrangement wherein it is impossible for an operator to accidentally or erroneously ground a live bus. This is quite possible in the switching sys-

tems of the past wherein the respective disconnect switches were each independent of the other and some disastrous results have been known to follow from such erroneous operation of the disconnect.

55

We mount all of the disconnect switches upon a single operating shaft which, by successive actuations, is adapted to effect the various switching arrangements. The entire switching mechanism is enclosed in a grounded casing and is adapted to be immersed in a bath of insulating liquid within the casing. Because of the use of the insulating bath the various switches may be made of smaller sizes than would be necessary on air break switches of the same capacity and, because of the fact that the device is completely encased, it can be used equally well for either outdoor or indoor installations.

60

65

We have further invented a new contact clip which is particularly useful in this type of mechanism, although these contacts may also be used on other forms of switches. The contact comprises a pair of contact shoes which are adapted to receive a switch blade between them and which are constantly pressed into engagement with one another by means of suitable springs. The contacts are mounted and electrically connected to a suitable frame which is preferably of a channel or U-shape and which serves as a terminal to which the electrical connections to the contacts may be made. The contacts are of the full floating type and are maintained in position by means of a set of leaf springs or the like which will permit the desired movement of the contacts in all directions.

70

75

80

85

The attainment of the above and further objects of the present invention will be apparent from the following specification taken in conjunction with the accompanying drawings forming a part thereof.

90

In the drawings:

95

Figure 1 is a diagram illustrating the circuit connections of our improved switch, the portions A, B, C, D, E, F and G illustrating the various circuit conditions established by the switch in its various positions;

100

Figure 2 is a top view of our improved switching device;

20 Figure 10 is a top plan view of a modified form of switching mechanism;

Figure 11 is a front view of the mechanism shown in Figure 10; and

25 Figure 12 is a diagrammatic sketch showing the relationship of the contacts and the respective switch blades.

Reference may now be had more particularly to the diagrammatic sketch of Figure 30 1. In this diagram a main bus is indicated by the letter M and a transfer bus is indicated by the letter T. An outgoing line circuit is indicated at 1, an oil circuit breaker at 2, and a regulator at 3. The switching 35 device for establishing the various desired connections is indicated by the reference letter S. This system includes a number of outgoing line conductors such as the conductor 1, each of these outgoing line conductors having available thereto an oil circuit breaker such as the breaker 2, a regulator such as the regulator 3, and a switching device such as the switching device S for establishing the desired connections with the main or 40 with the transfer bus M or T respectively, which busses are common to all of said switching devices.

The switching device is provided with a 45 regulator contact 5, a main bus contact 6, a line circuit contact 7, another regulator contact 8, a transfer bus contact 9 and a grounded contact 10. The regulator 3 is connected between the contacts 5 and 8 whereas the main bus is connected to the contact 6 through the oil circuit breaker 2. The switching device is provided with a number of switch blades which are adapted to contact with the 55 respective contacts 5 to 10, inclusive, upon suitable actuation of the switching device. These 60 switch blades are indicated at 15 to 20, inclusive. The blades are mounted upon a common shaft which is adapted to be turned to bring the various blades into and out of engagement with their associated contact. The 65 contacting ends of the blades are arcuate and

of various lengths, the contacting portions of the respective blades being angularly disposed with respect to one another to obtain the desired sequence of engagement with the respective contacts. In the switch herein 70 illustrated the contact 15 has a contacting portion of 78 degrees the contact 16 has a contacting portion of 179 degrees, the contact 17 comprises two portions 17a which is of a width of 95 degrees and the contact 17b 75 which is of a width of 45 degrees, said two contacting portions being spaced apart by 118 degrees. Likewise the contact 18 comprises a contacting portion 18a of 44 degrees and a contact portion 18b of 80 degrees, said contacting portions being 157 degrees apart. The contact 19 extends for 145 degrees and the contact 20 extends for only 32 degrees. These sizes are pointed out merely by way of illustration it being understood that we 80 are not limited to the precise sizes herein set forth since larger or smaller contacts may be used if desired.

The three blades 15, 16 and 17 are electrically connected together and in a like manner the three blades 18, 19 and 20 are electrically connected together but insulated from the first mentioned three blades. The blades 18, 19 and 20 are connected to the terminal 7 by means of a flexible conductor 21. When the switching device is in the position shown in the drawings the contact 8 is in engagement with the switch blade portion 18a and the contact 10 is in engagement with the switch blade 20. A ground connection is therefore established from the contact 10 through the switch blade 20 to the switch blade 18a and hence to one side of the regulator, and likewise by way of the conductor 21 to the contact 7 and the outgoing line circuit 1. The circuit established is therefore as indicated at A in Figure 1. Assume that the controller S is moved to the left. The switch blade 20 will leave the contact 10 and the switch blade 18a will leave the contact 8 before the blades 17a and 19 engage the contacts 7 and 9 respectively. During this interval, that is after the blades 20 and 18a have left their respective contacts and before the blade 19 engages the contact 9, the circuit will be open as indicated at B in the drawings. Further movement of the switching device will bring the switch blade 19 into engagement with the contact 9. This establishes a circuit from the transfer bus through the switch blade 19 and the common conductor 21 to the outgoing line circuit as indicated at C in the drawings. Slightly further movement of the controller brings the blade 17 into engagement with the contact 7. This, for the time being, is of no avail it being merely a preparatory movement which prepares a circuit to the main bus. In the meantime the transfer bus is feeding the outgoing line circuit 1. Further movement of 130

the switching mechanism brings the switch blade 16 into engagement with the contact 6. The outgoing line 1 is now being supplied with power from the main bus as follows: 5 From the main bus through the circuit breaker 2 and contact 6 to the switch blade 16, thence by way of the connection between the switch blade 16 and the blade portion 17a to the contact 7 and thence out to the line circuit. At the same time a circuit is established 10 from the main bus to the transfer bus, unregulated. This circuit extends from the main bus through the contact 6 and switch blades 16 and 17a to the contact 7, thence by way of the conductor 21 to the switch blade 19 which is still in engagement with the contact 9 and thereby supplies power to the transfer bus. Further movement of the switching mechanism will bring the switch 15 blade 15 into engagement with the contact 5 and a moment later it will bring the switch blade portion 18b into engagement with the contact 8. This will all take place before the switch blade portion 17a leaves the contact 7 due to the fact that the contacts are of a greater width than is necessary to bridge an angular gap such as indicated at 25 between the switch blade portion 17a and the switch blade portion 15. This gap is roughly 20 18 degrees whereas the contacts are of such a width as to extend over approximately 28 degrees of the arc of the blade. After the switch blades 15 and 18b have engaged their respective contact and before the switch 25 blade 17a has left its contact 7 there are no circuit changes over that shown in sketch D except that the regulator is connected between the points 6 and 7 of sketch D, said regulator being short circuited. The short circuit between the contacts 5 and 8 extends 30 as follows: From the switch blade 15 through the common connection to the blade portion 17a, thence through the contact 7 and conductor 21 which is connected to the three electrically connected blades, to the blade portion 18b that is in engagement with the contact 18. As soon as the switch blade portion 17a leaves the contact 17 upon further movement of the switching device this short circuit 35 across the regulator is opened and the regulator is connected in circuit as shown in the sketch E. Under these conditions the outgoing line circuit is being fed from the main bus through the regulator, and the transfer bus is also being fed from the main bus through the regulator. Upon further movement of the switching device the switch blade 19 will disengage the contact 9 while the switch blades 15, 16 and 18b are still in engagement with their respective contacts. 40 When this occurs the circuit will be established as shown in sketch F, the line circuit being fed from the main bus through the regulator. This circuit extends as follows: 45 From the main bus, through the oil switch

2 and the contact 6 to the blade 16, thence by way of the blade 15 and the contact 5 through the regulator to the contact 8 which is still in engagement with the switch blade portion 18b, thus establishing a connection through the conductor 21 to the contact 7 and out through the line 1. At this time the contact 9 is not in engagement with the switch blade 19, hence the transfer bus is not connected in circuit by this switching device although it is to be understood that at the same time another switching device such as the device S may be in a position to connect the main bus to the transfer bus over a circuit such as is shown in sketch D or in sketch E. Upon further movement of the controller the switch blade portion 17b will engage the contact 7 before the blade 15 disengages the contact 5 and before the blade portion 18b disengages the contact 8. As soon as the switch blade portion 17b engages the contact 7, and before the blade portions 15 and 18b disengage their respective contacts, a short circuit is established across the contacts 5 and 8 as follows: 50 From the contact 5 through the blade 15 to the blade 17b and the contact 7, thence by way of the conductor 21 to the blade portion 18b which is in engagement with the contact 8. A moment later the switch blade 15 and the switch blade portion 18b move out of engagement with their contact. This merely serves to disconnect from the circuit shown at F the regulator, which was previously short circuited. A circuit such as is shown at G in Figure 1 is now established. In this circuit the outgoing line 1 is being fed directly from the main bus without the regulator. This circuit extends from the main bus, through the oil circuit breaker 2 and the contact 6 to the switch blade 16, thence by way of the switch blade portion 17b, which is permanently connected to the switch blade 16, to the contact 7 which is the terminal for the line circuit 1. Further movement of the controller for moving the switching device is prevented by the provision of a stop which is engaged before the switch blade 16 leaves its contact 6. 55 When the switching device has been moved to its extreme position so as to obtain the circuit shown at G it can be moved no further in the same direction. It can of course be operated in the reverse direction. From any of the intermediate positions the mechanism may be moved in a forward or in a reverse direction as desired. From the above description it may be seen that we have devised a switching mechanism and circuit connections whereby it is possible to effect the connection or disconnection of a regulator to an outgoing circuit without interrupting the outgoing circuit and also to establish connections to a main bus or to a transfer bus or to provide interconnection between the 60 65 70 75 80 85 90 95 100 105 110 115 120 125 130

buses all without interrupting the outgoing line circuit.

Reference may now be had more particularly to Figures 2 to 7, showing the construction of a switching device embodying the principles of our invention. The switching device is mounted in a tank 40 which comprises a bottom 41, transverse sides 42 and 43, and longitudinal sides 44 and 45. The tank is also provided with a cover 46 which may be bolted or otherwise removably secured to the top of the tank and for this purpose angle iron frame members 47 are secured to the edges of the side walls. A switch base 50, formed of slate or other suitable insulating material is mounted within the switch tank 40 and spaced from the bottom 41 thereof. This base may be mounted by suitable brackets 51 which space the base from the bottom 41 of the switch casing. The base 50 constitutes a support for the switch contacts 5, 6, 7, 8, 9, and 10, each of these contacts being of a construction such as is shown more particularly in Figures 5 and 6 to which reference will be had as the description proceeds.

An operating shaft 60 is rotatably mounted within the casing 40. This switch shaft is made of wood or other suitable insulating material and is preferably of a square section although it may be of any other section if desired. The square shaft 60 is rounded adjacent its two ends and it is supported by means of bearings in suitable supports. The supports herein shown each comprise an upright channel shaped member 63 having a central opening therein through which the shaft 60 extends, said supporting member being braced by means of two braces 64—64 that extend between the base 50 and the flanges of the channel 63.

Bars 68 and 69 are secured to one or more sides of the switch shaft 60. The bars 68 connect the three blade members 15, 16 and 17 while the bars 69 connect the three blade members 18, 19 and 20, said two sets of blades being insulated from one another by the portion of the operating shaft which is indicated at 68' and which does not have any strips such as 68 or 69 extending thereover. The switch blades 15 to 20, inclusive, each comprise a disc portion of copper or other suitable metal, said blades being provided with a central square opening whereby the blades may be mounted upon the operating shaft 60. The blades are secured to the shaft by means of suitable angle brackets 69'—69' which are bolted to the operating shaft and also to the switch blades. Suitable angle brackets 70—70 serve to further secure the blades to the shaft and also to the respective conducting strips 68 and 69.

The construction of one of the contact blade members is shown in Figure 7. In this figure we have shown, for illustrative purposes,

the blade member 17. This blade consists of a plate which may be about one-eighth of an inch thick, although other sizes may be used if desired, and is provided with a square hole for mounting it upon the switch shaft. The blade is provided with two contacting portions indicated at 17a and 17b respectively, said contacting portions being of different sizes in order to obtain the desired sequence of connection with its contact 7 (Figures 1 and 3). The portion 17a is shown as extending through an arc of approximately 95 degrees whereas the portion 17b extends through an arc of approximately 45 degrees, these arcuate portions being properly spaced with respect to the square hole to procure the desired relationship upon the switch operating shaft. The blade is provided with sets of holes to facilitate mounting of the blades, said holes being adapted to receive bolts, rivets or the like for connecting the blade to the angle members 69' and 70.

The side wall 44 of the switch casing 40 is provided with six spaced openings in which are mounted six low tension transformer entrance bushings indicated at 81 to 86, inclusive. Conductors 88 extend through the respective bushings for extending a circuit into the casing. The transformer entrance bushings are provided with insulating portions both inside and outside of the wall 44 of the switch housing and suitable connectors 87 are bolted or otherwise secured to the portion of the conductors 88 within the housing, said connectors being secured to the conductor portion 88 by means of suitable nuts 89—89. The connector members 87 consist in general of L-shaped copper bars that extend beneath the slate base 50 and are secured thereto and to the corresponding contacts 5 to 10 respectively by means of bolts 92 which extend through suitable openings in the slate base 50 and are threaded into openings in the base of the contact supporting frames to be presently described.

Reference may now be had more particularly to Figures 5 and 6 showing the construction of one of the switch contacts such as the contacts 5 to 10 with which the switch blades are adapted to contact. The contact comprises a frame 101 of a channel-shaped or U-shaped section. The base of the frame is indicated at 102 and the flanges are indicated at 103 and 104 respectively. The base or web 102 is provided with two tapped holes 106 and 107 for receiving the bolts 92 for rigidly mounting the contact upon the slate base 50 and for establishing an electric circuit between the contacting strap 87 and the contact. The frame 101 is made of copper or other suitable metal of high conductivity as are also the screw members 92. A pair of contact shoes 110 and 111 are disposed between the flanges 103 and 104 of the frame 101. Each of the contact shoes is made of

copper tubing through which a flexible braided conductor 114 is extended, the tubing being thereafter flattened upon itself in a suitable press to compress the tubing upon the flexible conductor and to present a flat contacting surface on one side. A pair of flat leaf springs 116 and 117 which are bent in a generally U-shape are secured to the opposite ends of the contact shoes 110 and 111 by means of rivets or the like as indicated at 118. Each of the rivets 118 passes through holes in the respective contact shoes from the rear thereof and serves to secure the web portion of the U-shaped spring to the contact. The ends 15 of each of the rivets 118 adjacent the front face 115 of the contact are preferably made flat so as not to interfere with the sliding movement of the blade between the contact shoes during the opening or closing of the switch. To facilitate this the rivet holes in the contact shoes are preferably countersunk. The opposite ends of the springs 116 and 117 are free and are guided between two strips of metal 120 and 121 that are secured 20 to the flanges of the frame 101 by means of suitable rivets or screws 122. The inner strips 121 may be omitted if desired since the outer strips 120 effectively hold the springs against side movement. The ends of the braided conductors 114 have suitable terminals 125 secured thereto. These terminals may comprise merely short lengths of tubing of copper or the like into which the ends of the flexible braided conductors are passed and which are 25 thereafter compressed upon the ends of the conductors by pressing the same in a suitable press. The terminals 125 are removably secured to the contact frame 101 by means of suitable bolts 126—126 that extend through 30 suitable openings formed in the terminals 125 and are threaded into suitable openings in the flanges 103 and 104. The bolts 126 are preferably, although not necessarily, formed of copper or other suitable metal of high electrical conductivity. The ends of the contact shoes 110 and 111 are curved away from one another as indicated at 128—128 in order to facilitate the movement of a switch blade 35 between the two contact shoes. The springs 116 and 117 constantly urge the two contact shoes toward one another so that their contacting faces are in engagement when the switch is open. When a switch blade is moved between the contact shoes it forces the contacting shoes apart as it moves between them. The springs 116 and 117 maintain the contacting shoes against the opposite sides of 40 the switch blade and insure the maintenance of a suitable contact pressure between the contacts and the switch blade. It is to be noted that the contact shoes are freely floating and may readily adjust themselves to any angular displacement of the switch blade, should this be necessary.

65 Referring now more particularly to Fig-

ures 2 and 3 we shall explain how the conductor 21 (Figure 1) is connected between the contact 7 and the switch blades 18, 19, and 20. The conductor 21 takes the form of a bar of copper or the like which is placed above the L-shaped connector 87 that extends to the third switch contact from the left, that is the contact 7. The bolts 92 which connect this connector strap 87 with the contact 7 and which secure the contact 7 to the slate base 50 are therefore made slightly longer than are the bolts provided for the other contacts. This copper strap 21 extends along the bottom of the slate base 50 to the right hand side thereof where it connects with an upwardly extending flexible braided copper conductor 143 having suitable terminals at both ends thereof which is connected at one end to the bar of copper 69 by means of a suitable bolt 145 and is connected at its other end to the strap 21 by means of a copper bolt or the like, thereby establishing a connection between the contact 7 and the three switch blades 18, 19 and 20 through the strap 21, and the copper bars 69. Suitable protecting boards 147 and 148 are interposed on the two sides of the flexible conductor 143 in order to prevent the inadvertent touching of the flexible conductor against any of the other parts of the mechanism. These protector boards are made of fiber or other suitable insulating material and are bolted in place by means of suitable brackets 150.

One end of the shaft 60 extends through the side wall 42 of the switch housing, said extended end being indicated at 155 in Figure 3. A suitable handle 156 is provided for rotating the shaft to actuate the switch blades. Beveled lugs 160—160 are mounted in pairs upon the end wall 42, said lugs being located in a circle about the shaft portion 155 as a center. These lugs are provided for bringing the handle to rest at definitely located positions, the corresponding positions of the switch blades, as indicated at A to G in Figure 1, are indicated opposite each of the sets of lugs upon the side wall 42 of the switch housing.

The switch casing is filled with oil or other suitable insulating liquid to a level appreciably above the top of the contacts 5 to 10, inclusive, so that any arc that may be drawn between the corresponding switch blades will be quenched in the liquid. For this reason it is necessary to make the switch casing oil tight. A plugged hole 165 is provided at the bottom of the side wall 42 for facilitating the draining of the switch casing.

Reference may now be had to Figures 8 to 11, inclusive, showing a modified form of our mechanism. This switch mechanism comprises a top or cover casting 200 from which the entire switch operating parts including the blades, as well as the contacts, are mounted. This cover casting may be

supported in the manner customary with oil switches. An oil tank 201, providing a bath of insulating oil for the contacts and the switch blades, is suspended from the cover casting 200 by means of a series of spaced bolts 202 which extend through suitable openings in angle iron members 203 that are secured on the outside of the tank 201. Five terminal bushings 211 to 215 extend 10 into the switch casing from the cover. Each terminal bushing comprises an insulator bushing 217 which extends through an opening in the cover casting 200, and is suitably supported from the cover to prevent the 15 entrance of moisture or other foreign matter into the casing. A suitable gasket 218 may be provided for this purpose. A conductor 220 extends through the insulator 217, the space between the conductor and the insulator being filled with a suitable compound indicated at 221. A terminal clip 222 is connected to the conductor 220 on the outside of the switch mechanism, and a contact is mounted upon this conductor on the inside 25 of the switch mechanism. The terminal bushings 211 to 215 are of a similar construction. This switching mechanism is adapted to establish electrical connections between a main bus, a transfer bus, a regulator, an outgoing line circuit, and ground in a manner analogous to that of the switch previously described. To accomplish this end the terminal 222 at the end of the conductor in the bushing 211 is connected to the outgoing line 30 circuit corresponding to the circuit 1 of Figure 1. The contact at the end of the conductor that extends through the bushing 211 therefor corresponds to the contact 7 of Figure 1 and will therefore be referred to as contact 35 7'. The terminal at the end of the conductor within the bushing 212 is connected to one side of an oil circuit breaker, the opposite side of the oil circuit breaker being connected to the main bus as shown in Figure 40 1. The contact at the end of the conductor within the bushing 212 therefore corresponds to the contact 6 of Figure 1 and will therefore be referred to as contact 6'. In a like manner the terminals at the outer end of the 45 conductors extending through the bushings 213 and 215 are connected to the opposite sides of a regulator. The contacts mounted within the housing and at the ends of the conductors extending through the bushings 50 213 and 215 therefore correspond to the contacts 5 and 8 respectively of Figure 1 and will therefore be referred to as 5' and 8' respectively. The terminal on the outer side of the conductor that extends through the 55 bushing 214 is connected to the transfer bus and the contact within the switch housing and at the opposite end of this conductor therefore corresponds to the contact 9 of Figure 1 and will therefore be referred to as contact 9'. A grounding terminal 225 is pro-

vided on the top of the casting 200, said terminal being connected within the switch housing to a suitable contact which corresponds to the grounding contact 10 of Figure 1 and will therefore be referred to as the 70 contact 10'. The contacts 5' to 10' inclusive may be of any preferred construction and as shown comprise two spring pressed contact shoes 230 mounted in an inverted U-shape contact holder 231 which is secured to the 75 bottom of the conductors 220 within the respective insulating bushings. The contact shoes 230 are maintained in engagement with one another and are adapted to be spread apart by a switch blade which moves between 80 them, the springs maintaining the contact shoes in engagement with the opposite faces of the switch blade.

A square shaft 240 of suitable insulating material is rotatably mounted within the 85 switch casing, said shaft being supported by two brackets 241 and 242 extending downwardly from the cover casting 200 and provided with a split bearing 244. The ends of the shaft 240 that are within the bearing 90 portion 244 are rounded and are provided with a metal collar to facilitate the turning of the shaft within the bearings. The bracket supports 241 and 242 are substantially triangular, the base of the triangle being bolted or otherwise suitably secured to the under side of the cover casting 200.

A circular switch blade 250 is mounted upon the shaft 240 so as to be rotated therewith. This may be accomplished by providing a collar 251 which is keyed to the shaft and which is provided with a flange 252 to which the switch blade 250 may be bolted. This blade extends through an arc of approximately 155 degrees and is adapted to successively engage the contacts 5', 6' and 7'. These contacts are located in the same plane and are spaced approximately 90 degrees apart, as may be seen in Figure 8. Upon rotation of the switch blade 250 in a counter-clockwise direction as seen in Figure 8, this blade is adapted to disengage from the contact 7' before the opposite end thereof engages the contact 5'.

A switch blade 260 comprising blade portions 260a and 260b is mounted upon the shaft 240 in spaced insulated relationship to the switch blade 250. This blade may be mounted in place by means of a collar 261 which is keyed to the shaft 240 and is provided with flanges 262 to which the blade sections may be bolted or otherwise rigidly secured. The contact portion 260b may be of a width of approximately 65 degrees and the contact portion 260a may be of about the same width. These contacts may be spaced oppositely one another, that is, with their center lines 180 degrees apart. These blades are adapted to be moved into and out of engagement with the contacts 8' and 9'. When 130

the switch is in the position shown in the drawings the contact portion 260a is in engagement with the contact 9' but the contact 260b is not in engagement with either of the contacts 8' or 9'. The contact 8' is mounted directly in back of the contact 5' of Figure 8 whereas the contact 9' is mounted midway between the contact 6' and 7' as seen in Figure 8.

10 A switch blade 270 is mounted upon the shaft 240, said blade being bolted or otherwise suitably secured to the collar 261. This collar is made of copper or other metal of high electrical conductivity thereby placing 15 the blade 270 in constant electrical connection with the blade 260. The blade 270 is adapted to be moved into and out of engagement with the grounded contact 10', which is located as shown in Figure 9 and directly 20 in back of the contact 6' of Figure 8. The switch blade 270 is of a small size extending through an arc of approximately 20 degrees and disposed as shown in Figure 11 so as to engage the grounded contact 10' upon a rotation of the shaft 240 through an angle of 25 approximately 270 degrees from the position shown in the drawings.

The contact 7' is permanently electrically connected to the collar 261 by means of a 30 flexible braided conductor 275 that is connected at one end to the stud at the end of the conductor 220 upon which the contact 7' is mounted, said conductor 275 being connected at its opposite end to the copper collar 261.

35 For this purpose the conductor 275 may be provided with a terminal lug 276 comprising a copper tube flattened upon the flexible braided conductor. This terminal lug may be bolted or otherwise rigidly secured to the 40 collar 261 and in firm electrical contact therewith. This conductor 275 corresponds to the conductor 21 shown in the circuit diagram of Figure 1. The relative location of the contacts 5' to 10', inclusive, and of the corresponding switch blades 250, 260 and 270 45 is illustrated diagrammatically in Figure 12. When the shaft 240 is rotated to rotate the switch blades the various circuit connections, to be more fully explained as the description 50 proceeds, are set up.

The portion of the shaft 240 that extends beyond the bracket 242 is provided with a sprocket 280 which is in mesh with a sprocket chain 281 that extends around an actuating sprocket 282 mounted upon an actuating 55 shaft 283. The shaft 283 is supported in a suitable bearing 284 formed in a housing at the top of the cover casting 200. An actuating mechanism 285 is secured to the cover 60 casting, said shaft 283 extending into this actuating mechanism. A gear 286 is keyed to the shaft 283 and is in mesh with a pinion 287 supported upon a stud 288 and adapted to be driven by an electric motor 290 which may 65 be controlled from a remote point. The end

of the shaft 283 extends outside of the housing 285 and is provided with a pointer 291 which is keyed thereto and moves over an indicator 292, which has seven indications thereon indicating the seven positions which this shaft 283 may assume. These seven positions correspond to the positions A to G of Figure 1 and indicate the various circuits that are established when the shaft 283 is in the corresponding positions. The shaft 240 70 is rotated through an angle of 45 degrees between successive positions as is also the shaft 283 although it is apparent that a step-up gear ratio may be provided between the gears 280 and 282 so that the shaft 283 may move through a different angle for a 45 degree movement of the shaft 240. The end of the shaft 283 is provided with a square hole into which an operating handle may be inserted to turn the shaft 283 independently of 75 the motor 290 when it is desired to actuate the switching mechanism by hand. The gear 286 is provided with a pair of projecting stops 295 and 296 for limiting the extent of 80 rotation of the gear. As shown in Figure 11, the stop 295 bears against the pinion 287 and prevents further rotation of the gear 286 in 85 a clockwise direction. Counter-clockwise rotation of this gear is however permissible until the stop 296 bears against the opposite side of the pinion, thereby limiting the extent of permissible rotation in the counter-clockwise direction.

The tank 201 is provided with a capped opening 298 for facilitating the filling of the tank with oil or other insulating liquid used. The tank is filled with oil or other suitable insulating liquid to a level 299 (Figure 9) thereby completely submerging the blades as 90 well as the contacts in the bath of insulating liquid. A plug 300 is provided for facilitating the draining of the tank. In addition the tank is provided with handles 301 and 302 (Figure 11) to facilitate the handling 95 of the tank when the same is being bolted into position or being removed from its position.

Reference may now be had more particularly to Figure 12 showing, in diagrammatic form, the circuit connections for the controller shown in Figures 8 to 11. The electrical connections are as indicated in this figure, said connections being the same as have been previously described and being substantially similar to the connections shown in Figure 1. The switch blades are shown in the positions that they occupy when the controller is in position 1. In this position the outgoing circuit 1 is connected to the main bus through 110 the oil circuit breaker 2, and a connection is also established from the main bus through the oil circuit breaker 2 to the transfer bus, both of these circuits being unregulated. The first mentioned circuit extends from the main bus through the oil circuit breaker to the 115 120 125 130

switch contact 6', thence by way of the switch blade 250 to the switch contact 7' and the circuit line 1. The second mentioned circuit extends from the contact 7' through the 5 permanent jumper connection 275 previously described, to the collar 261 which connects the switch blade 260 with the switch blade 270, the circuit then extends from the switch blade section 260a through the contact 9' to 10 the transfer bus. This circuit corresponds to the circuit D of Figure 1. From this position the controller can be moved only in the counter-clockwise direction since the stop 295 (Figure 11) prevents clockwise rotation from 15 this position. The successive circuit positions are obtained by rotating the switch blades through 45 degree angles. Upon the first 45 degree rotation of the switch blades, the blade 250 still maintains a connection be- 20 tween the contact 6' and the contact 7' thus maintaining the connection between the main bus and the outgoing line. The blade portion 260a, however, is moved out of engagement with the contact 9' thereby breaking 25 the connection between the main bus and the transfer bus. The circuit now established corresponds to the circuit G of Figure 1. Upon the initial rotation of the switch blade to the third position the blade 250 engages the 30 contact 5' and the blade portion 260a engages the blade 8', both of these blades engaging their contact before the opposite end of the blade 250 disengages the contact 7'. During this period the regulator is short circuited 35 while the circuit connection between the blade 6' and the blade 7' is uninterrupted. This short circuit connection extends from the contact 5' through the blade 250 to the contact 7', thence by way of the flexible con- 40 ductor 275 to the blade portion 260a and the contact 8'. A moment later when the controller reaches its full third position the blade 250 moves out of engagement with the contact 7' thus removing the short circuit 45 from across the regulator. The circuit to the outgoing line conductor now extends from the main bus and the contact 6' through the switch blade 250 and the contact 5', through the regulator 3 and the contact 8' to the 50 switch blade 260 and thence by way of the jumper 275 to the outgoing line circuit 1. The outgoing line circuit is now being fed from the main bus through the regulator. This circuit corresponds to the circuit F of 55 Figure 1.

To establish the next circuit connection the controller is moved another 45 degrees in the counter-clockwise direction, that is, to a position 135 degrees from the position 60 shown in Figure 12. The blade portion 250 still maintains connections between the contact 6' and the contact 5' while the blade portion 260a still remains in engagement with the contact 8'. At this time the blade por- 65 tion 260b has moved into engagement with

the contact 9' thus establishing a circuit to the transfer bus from the main bus by way of the regulator. This last mentioned circuit extends from the contact 6', through the blade 250 to the contact 5' and the regulator 70 3 to the contact 8', thence by way of the switch blade portion 260a to the switch blade portion 260b in engagement with the contact 9' that is connected to the transfer bus. At this time the outgoing line circuit 1 is 75 also being fed from the main bus through regulator. The circuit connections at this time correspond to the circuit E of Figure 1. An additional 45 degree movement of the switch blade brings the blades to a position 80 180 degrees from that shown in the drawings, which is the fifth circuit position. At this time the contact 6' is not engaged by the blade 250, hence the main bus is not in circuit through the controller. The switch blade 260a is out of engagement with the contact 8', hence the regulator 3 is not in the circuit. The outgoing line circuit is now being fed from the transfer bus by way of the switch blade portion 260b which is in 85 engagement with the contact 9', the circuit extending from the switch blade portion 260b through the jumper 275 to the outgoing line circuit. This circuit corresponds to the circuit C as in Figure 1. 90

The sixth position of the controller is the open circuit position and is obtained by rotating the switch blade through an additional 45 degrees, that is through an angle of 225 degrees from the position shown in Figure 12, the direction of rotation being counter-clockwise. At this time all of the switch blades are out of engagement with any of their contacts, and the connections are shown in the sketch B of Figure 1. 100

An additional 45 degree rotation of the switch blades in a counter-clockwise direction will bring the blades in a position of 270 degrees from the position shown in Figure 12. At this time the switch blade 270 engages the 105 grounded contact 10' and the switch blade 260b engages the contact 8', the blade 250 engaging the contact 7'. At this time the main and the transfer bus are not connected to their corresponding switch blades and the 110 circuit connections are as shown in the sketch A. The ground potential extends from the contact 10', through the blade 270 and the collar 261 to the blade 260b which is in engagement with the contact 8', thereby 115 placing ground potential upon one side of the regulator. This ground potential is also extended to the outgoing line circuit by way of the jumper 275 which is connected to the contact 7'. 120

It may be seen that the sequence of the establishment of connections by means of the mechanism shown in Figures 8 to 11, inclusive, is substantially the same as is obtained by the controller shown in Figure 1, differ- 125 130

ing therefrom only in that the circuit connection shown at D of Figure 1 is obtained prior to the circuit G and, if this circuit D were placed immediately to the right of the circuit G of Figure 1 then the sketches would represent the sequence of the establishment of connections by the controller shown in Figures 8 to 11, inclusive. It is to be understood that the sequence of the establishment 10 of the connections as shown may be varied without departing from the spirit of our invention. It is, however, preferable to have the connections established in such a manner that there is no interruption of the line circuit 15 1 when switching from the main bus to the transfer bus or vice versa or during the connection or disconnection of the regulator 3 in the circuit.

In compliance with the requirements of the 20 patent statutes we have herein shown and described a few preferred embodiments of our invention. It is, however, to be understood that the invention is not limited to the precise embodiments herein shown, the same 25 being merely illustrative of the invention.

What we consider new and desire to secure by Letters Patent is:

1. A switch comprising a casing adapted to contain an insulating liquid, a plurality 20 of bushings extending into the casing, a line connection, main and transfer bus connections and regulator connections all extending through said bushings and terminating in separate contacts below the liquid level in the 25 casing, a switch shaft in the casing, and switch blades mounted on the shaft for engagement with the respective contacts and selectively establishing circuit connections between them, said switch blades and contacts 30 being disposed to maintain the circuit to the contact terminating the first mentioned connection uninterrupted during the selective switching movement of the shaft, the blade engaging one of the regulator contacts being 35 electrically connected to the main bus switch blade and to the line switch blade.

2. A switch comprising a casing adapted to contain an insulating liquid, a plurality 40 of bushings extending into the casing, a line connection, main and transfer bus connections and regulator connections all extending through said bushings and terminating in separate contacts below the liquid level in the 45 casing, a switch shaft in the casing, switch blades mounted on the shaft for engagement with the respective contacts and selectively establishing circuit connections between them, said switch blades and contacts being disposed to maintain the circuit to the contact terminating 50 the first mentioned connection uninterrupted during the selective switching movement of the shaft, the blade engaging one of the regulator contacts being electrically 55 connected to the main bus switch blade and to the line switch blade, and the blade engag- 60

ing the other regulator contact being electrically connected to the transfer bus switch blade.

3. An oil switch comprising a rotatable 70 shaft, a switch blade mounted on the shaft, a plurality of bushing structures extending into the switch, contacts carried by the respective bushings, said switch blade being movable and being adapted to establish electrical connections between the contacts, another switch blade mounted on the shaft and insulated from the first mentioned switch blade, an electrical connection within the switch between one of the contacts and the second mentioned switch blade, a second set of bushings extending into the switch and carrying contacts adapted to be interconnected by the second mentioned blade, said shaft being movable to simultaneously actuate both blades, and a bath of insulating liquid immersing the blades and the contact. 75

4. A switch comprising a casing, a plurality 80 of bushings extending into said casing; a first conductor, second and third conductors, a pair of series connected conductors each extending into said casing through different ones of the bushings; contacts terminating each of the conductors; and cooperating with the contacts, switching means for establishing connections between the first conductor and the second conductor, switching means for establishing connections between the first conductor and the third conductor, and switching means for including and excluding the series connected conductors in one of said 85 connections and for establishing or disestablishing a connection between the second and the third conductors through the series connected conductors or independently thereof at will; said three mentioned switching means comprising a switch shaft, and a plurality of blades mounted on the switch shaft and angularly disposed with respect to one another to maintain a connection between the first conductor and one or the other of the two second 90 mentioned conductors throughout the switching operation. 100

5. A switch comprising a casing, a plurality 105 of bushings extending into said casing; a first conductor, second and third conductors, and a pair of series connected conductors each extending into said casing through different ones of the bushings; contacts terminating each of the conductors; and cooperating with the contacts, switching means for establishing 110 connections between the first conductor and the second conductor, switching means for establishing connections between the first conductor and the third conductor, and switching means for including and excluding the series connected conductors in one of said 115 connections and for establishing or disestablishing a connection between the second and the third conductors through the series connected conductors or independently thereof 120 125 130

at will; said three mentioned switching means comprising a switch shaft, and a plurality of blades mounted on the switch shaft and angularly disposed with respect to one another to 5 maintain a connection between the first conductor and one or the other of the two second mentioned conductors throughout the switching operation, and including a permanent connection between the contact terminating 10 the first mentioned conductor and at least one of the blades cooperating with the other contacts.

6. In an electric switch, a rotatably mounted shaft of insulating material and non-circular in cross section, two sets of switch blades mounted on the shaft and including means embracing the shaft, a conducting bus on the shaft connecting the blades of one set, another conducting bus connecting the blades of 15 the other set, and angle members connecting the blades to the respective buses and securing the blades in position on the shaft.

7. A single phase switch comprising a casing containing a bath of insulating liquid, a 20 cover therefor, and switching means suspended from the cover and depending into the insulating bath, said switching means comprising a rotatable shaft, a plurality of switch blades mounted thereon and laterally spaced 25 from one another, a plurality of sets of bushings supported by the cover and extending into the casing, said bushings supporting contacts adapted to be engaged by the respective 30 blades, the contacts of one set being angularly disposed and successively engaged by one of the blades in its movement, and the contacts of the other set being also angularly disposed and successively engaged by another one of 35 the blades in its movement, and connections 40 between one of the blades and a contact engaged by the other blade.

8. A rotary switch comprising a top structure, a pair of brackets suspended from said top, a rotary shaft supported by said brackets, a plurality of spaced arcuate shaped blade members mounted on said shaft, insulating bushings depending from said top structure and supporting each a contact, said contacts being disposed in the arc of a circle and 45 adapted to be engaged by one of said blades in its different positions, other insulating bushings also depending from said top structure and supporting contacts engageable by the other blades, operating means for the 50 shaft, said operating means extending downward from the top structure, and a casing suspended from the top structure and together with the top structure enclosing the switch mechanism.

60 9. In a system wherein there is a main bus, a transfer bus, an outgoing circuit, a plurality of disconnect switches for connecting the

circuit to either of the buses and for interconnecting the buses, a regulator, disconnect switches for selectively connecting and disconnecting the regulator in the outgoing circuit and for including and excluding the same from the interconnection between the buses, the combination with said switches of common actuating means for simultaneously actuating all of them, said switches being angularly disposed with respect to one another to effect the above mentioned connections in the various positions of the actuating means all without opening the outgoing circuit.

10. A high voltage electric system comprising a main bus, a transfer bus, a line, a regulator, and means for selectively connecting the line to the main bus or to the transfer bus at will and for including or excluding the regulator in one of said connections at will, said means comprising a multiple circuit multiple position switch establishing the various line connections in its various positions, said switch being of a circuit interrupting capacity substantially less than required for the circuits involved; and an oil circuit breaker for interrupting the circuit.

11. A high voltage electric system comprising a main bus, a transfer bus, a line, a regulator, and means for selectively connecting the line to the main bus or to the transfer bus at will and for including or excluding the regulator in one of said connections at will, said means comprising a multiple circuit multiple position switch establishing the various line connections in its various positions, said switch being of a circuit interrupting capacity substantially less than required for the circuits involved, and including contact making means establishing successive line connections prior to the opening of the previous connections as the switch is moved to its successive connection positions; and an oil circuit breaker for interrupting the circuit.

12. An electric system wherein there is a first bus, a second bus, a line, a regulator, and switching means for selectively connecting the line to either bus and for interconnecting the buses and for including and excluding the regulator in certain of said connections, characterized in that the switching means comprises a multicircuit controller of a circuit interrupting capacity substantially below that required for the system, and an oil circuit breaker for interrupting the circuit.

In witness whereof, we hereunto subscribe our names this twenty-fifth day of June, A. D. 1930.

TITUS G. LE CLAIR.
CHARLES M. GROSS.
